UNITED STATES PATENT OFFICE.

CHARLES JOHNSON, OF CHICAGO, ILLINOIS.

RECEPTACLE.

1,149,266.

Specification of Letters Patent. Patented Aug. 10, 1915.

Application filed February 15, 1913. Serial No. 748,675.

To all whom it may concern:

Be it known that I, CHARLES JOHNSON, a citizen of the United States, and a resident of Chicago, in the State of Illinois, have invented certain new and useful Improvements in Receptacles, of which the following is a specification.

My invention relates in general to receptacles, and more particularly to sectional 10 receptacles and has special reference to the provision of an improved type of receptacle including a variable number of units.

The principal objects of my present invention are the provision of an improved 15 structure of the type referred to characterized by a flexible, and preferably detachable, connection between the several receptacle units, whereby they may be readily moved relatively to each other, and thereby access 20 may be had to the interior of any one of the several units without removal or disturbance of any other one of the units or of the contents thereof; the provision of an article of the class referred to characterized by the 25 provision of means for locking the units in closed relation; and, similarly, with means for sustaining them in predetermined open position; the provision of an improved form of unit structure by the employment of 30 which the size of the receptacle may be expanded as desired; the provision in an article of the character referred to, of means for preventing tilting thereof; together with such further objects as may hereinafter appear.

While I have in the present case shown my improvements as applied to a box-like structure of the form convenient for the storage of garments and like articles, it is 40 obviously susceptible by variation in the size of the units, of embodiment in a large variety of other structures, such as trunks, tool boxes, legal blank cabinets, etc.

In attaining the stated objects and such 45 additional benefits and advantages as may be below disclosed, I have provided a structure shown in the accompanying drawings, wherein—

Figures 1, 2 and 3 are respectively a front, 50 a rear, and a sectional elevational view illustrating a preferred form of device; Fig. 3 being taken on the line III—III of Fig. 1.

Referring first to Fig. 1, it will be observed that I have here shown a plurality of 55 units, 10, 10^a and 10^b, each including front and back portions, 11 and 12, two sides

13—14, and a bottom 15, forming a box-like structure normally open at the top as is perhaps most clearly to be seen on inspection of Fig. 3. When a plurality of 60 units are assembled together as shown the bottom 15 of each of the higher units, such as is indicated at 10^a in Fig. 3, serves as a cover for the unit immediately below it, such as 10^b, and for closing the top of the uppermost unit (such as 10) I employ a top member or cover 16, which is, of course, formed separately from unit 10.

For a two-fold purpose, first, in order that the connection between two coöperating 70 units, such as are indicated at 10 and 10^a, may be rendered as nearly dust-tight as possible, and, second, to facilitate the assembly of the units, the bottom of each member 15 is disposed below the lower margins of the 75 front and back 11, and 12, and the sides 13—14 thereof, thereby permitting it to closely contact with the upper part of the interior faces of the front and back and side members of the unit immediately below. 80

To facilitate moving about of the structure formed by the assembled members I preferably provide the lowermost of the several members, 10, 10^a, and 10^b, adjacent the corners thereof, as indicated in Figs. 1 85 and 2, with suitable casters 17, preferably boring the bottoms of each of the several members 15 for the reception of the shank 18¹ of the casters, whereby the set of casters 90 may be conveniently detached from any one unit and applied to another unit in the event that it is desired to vary the relative arrangement of the several units.

For the purpose of connecting the several units together, I preferably employ a pair 95 of hinges 18, one leaf 19 of each hinge being arranged at the bottom of each of the units 10 and the other leaf 20 being arranged at the top thereof, so that when the several units are arranged in position the hinge members 19 and 20 are properly co-related and may be detachably connected in some suitable manner, such as by the use of a draw-pin 21.

For lifting a unit in order that access may 105 be had to the contents of the unit immediately therebelow, I preferably apply to each unit a handle 22; and for supporting the units in lifted position I preferably apply to some convenient point such as the sides 110 13—14 of each unit a coöperating pair of supporting members 23 (one not shown) a

convenient device for present purposes being the folding strut device shown in Fig. 3 which includes a pair of members 24, 25, pivoted to each other at 26 and to the side 5 13 at 27, the member 24 being in turn pivoted to a block 28 which has a shank 29 adapted to be removably inserted in a socket formed in the bottom 15 of the next higher unit, or of the cover 16.

10 For the purpose of fastening the several units in closed position, and of fastening the cover 16 in position upon the uppermost unit I preferably provide each unit adjacent its top and bottom with co-operating locking members 30, 31, respectively, and likewise 15 apply to the cover 16 members 30 as shown.

To the end that the assembled structure may be prevented from tilting rearwardly when opened up, as by raising the members 20 10 and 10^a in order to have access to the member 10^b I utilize one or more devices, each of which may include a pair of angles 32, 32, applied to the bottom of the members 15 for the reception of a movable foot piece 25 33 adapted to be slidably arranged therebetween, which foot piece may, when desired, be withdrawn and extended to the rear of the device as indicated in Fig. 3.

From the foregoing description of my improved receptacle, it will be apparent that 30 not only may access to the contents of any one of the units be readily had without disturbance of any of the others thereof, but

that the structure is susceptible of any desired variation in the number or arrangement of the units; and furthermore that by the employment of units of the character described, the use of a specially constructed bottom unit or base member is not necessitated.

Having thus described my invention and illustrated its use, what I claim as new and desire to secure by Letters Patent is:

1. A device of the character described comprising in combination a plurality of 45 flexibly connected receptacles, one forming a cover for the other, each of the receptacles being adapted to receive an anti-tilting device, and an anti-tilting device on one of the receptacles.

2. A device of the character described comprising in combination a plurality of 50 flexibly connected receptacles, one forming a cover for the other, each of the receptacles being provided with a pair of oppositely disposed angles to receive an anti-tilting device, and an anti-tilting device adapted to be slidably carried by said angles.

In testimony whereof I have hereunto signed my name in the presence of the two 55 subscribed witnesses.

CHARLES JOHNSON.

Witnesses:

OSCAR L. SCALBORN,
PANE CARPENTER.
